UNITED STATES PATENT OFFICE.

CLAUDE A. RENNER AND EDWIN A. RENNER, OF PERKASIE, PENNSYLVANIA.

SPARK-ARRESTER.

1,303,393.

Specification of Letters Patent. Patented May 13, 1919.

Application filed December 10, 1918. Serial No. 266,099.

To all whom it may concern:

Be it known that we, CLAUDE A. RENNER and EDWIN A. RENNER, citizens of the United States, residing at Perkasie, in the county of Bucks and State of Pennsylvania, have invented certain new and useful Improvements in Spark-Arresters, of which the following is a specification.

This invention relates to spark arresters, and more especially to those adapted for application to smoke stacks on railway locomotives, and the object of the same is to produce a smoke arrester of this type which is capable of being folded backward by the engineer so that the locomotive may pass through a tunnel or under a low bridge.

With this general end in view, the invention consists in the details of construction of the spark arrester itself and the mechanism for supporting it pivotally upon a locomotive boiler. The invention also comprises a special form of receptacle into which the soot is delivered, and a pivoted spout leading into said receptacle. The invention also comprises details hereinafter more fully described and claimed, and shown in the drawings wherein—

Figure 1 is a side elevation of the forward portion of a locomotive boiler with this improved smoke arrester on the same and a sectional detail of the cab with the actuating mechanism therein.

Fig. 2 is a sectional view through the stack and the hood receptacle.

Fig. 3 is a perspective detail of the receptacle and its spout.

Fig. 4 is a front elevation.

The boiler B leads forward from the cab C and near its front end it has a stack S just in rear of the headlight H. All these parts are of usual construction, and need no further amplification. As is well known, locomotive engines are now built so that the boiler and steam domes are as high as possible, whereas the stack is quite low so that it will pass under low bridges and through restricted tunnels without striking. Therefore, it is impossible to superpose upon the stack any considerable structure for gathering or arresting the sparks, because it will hit the overhead objects. Broadly speaking our invention contemplates the employment of a hood normally disposed above the stack, but capable of being folded back onto the top of the boiler so that it will not possibly strike anything overhead.

Coming now to the details of construction as set forth in the drawings, the hood 1 has a sheet metal body which is curved transversely over the top as seen in Fig. 4 and also curved longitudinally as seen in Fig. 1, preferably by being made in a plurality of members 2, 3, 4, connected together on oblique lines. Its bottom 5 may be curved transversely, and at its rear end this bottom plate nearly meets the rear end of the top plate 6 so as to produce a reduced outlet 7. The inlet is of ample size as indicated by the brace and the numeral 8 in Fig. 2, and in the normal position of the hood, this inlet overlies the stack S. A baffle or plate 9 practically closes the front end of the front member 2, whereas the top of the intermediate member has a small outlet 10 for smoke, the outlet being protected by an interior or baffle 11 to prevent sparks from rushing out the outlet and causing them to pass through the member 4 out the outlet opening 7 at the rear end of the hood. Coacting with the hood described above is what we call a spout shaped somewhat like a funnel. It is broadly indicated by the reference numeral 15, and it tapers from top to bottom and is made of sheet metal like the hood. Its larger upper end 16 underlies the outlet end 85 of the spout and is provided with a forwardly projecting lip 17 hooked upward at its extremity as at 18 to loosely engage under a rib 19 across the bottom of the hood, thereby connecting these elements in such manner 90 as to permit a certain relative motion between them as described below.

The receptacle broadly indicated by the numeral 20 is mounted directly upon the boiler B and has a door 21 in one side 95 through which the accumulations may be removed. It is a box-like structure also by preference of sheet metal, and in its top and rear is a large channel 22 across whose forward end extends a rod or bolt 23 upon 100 which the funnel 15 is pivotally mounted. When the rod stands upright as seen in Fig. 2, the cinders coming through the hood pass down through the spout and into the receptacle, wherein they may be collected by any 105 suitable means and from which they are withdrawn from time to time through the door 21. When this improved spark arrester is not in use, however, the hood is drawn to the rear as indicated in dotted 110 lines in Fig. 1 and this obviously swings the spout over to the rear on its pivot 23 so that

it lies within the channel 22. Yet the pivotal connection of rib 19 with the lip 17 permits the respective movements of the two elements without their becoming disengaged, 5 and therefore, when the hood is swung back to its active position as shown in Fig. 1, the spout is elevated and again ready for work.

While any suitable means may be employed for supporting the hood, we prefer to 10 mount it on a plurality of rods, and two on each side will answer. Each is pivoted at 30 at its lower end on an ear 31 on the boiler B, and each supporting element is made of a single rod extending upward through a 15 coiled spring 32 and connected with the upper end or coil thereof and a double element 33 passing down through the spring and connected at its lower end 34 with the lower end thereof. The upper end or bend of this 20 double element is in turn connected with an ear 35 at the side of the hood. By preference we employ one of these supports at the front and another at the rear and two more 25 on the other side as shown in Fig. 4, and their purpose is to support the hood in such manner that it will operate as described above, while yet drawing it downward with yielding force onto the top of the stack as 30 shown in Fig. 2. When now the engine is laboring and the smoke is driven with force up the stack, the hood may yield as the springs permit, while yet it will not be blown off the stack or dislodged from its proper place.

35 The actuating mechanism for swinging this device into place and out of place is composed mainly of a lever 40 located within the cab C and having a thumb-latch mechanism 41, and a rod 42 connecting this 40 lever with a rod 43 whose lower end is pivoted at 44 in an ear 45 on the boiler B. In fact, we prefer to use two of these rods, the second one numbered 43', being shown in Fig. 4, and the two rods are connected by a 45 cross bar 46 as seen. At its upper end each rod slides through a guide 47 carried by the hood 1 and may be threaded as shown in Fig. 1, and on the threads is a nut 48 beneath the guide so as to limit the descent of the 50 hood under the influence of the several springs 32, while yet permitting the hood to rise under the pulsation referred to above. When now the lever 10 is moved, the rod 42 draws on the swinging rod 43 which stands 55 over its pivotal support 44, and its upper end moves the guide 47 to the rear so that the entire hood is swung over to the position shown in Fig. 1 in dotted lines. Then the locomotive can pass under the lowest bridge 60 without striking the spark arrester and after it has passed the engineer can restore the hood to the position shown in full lines. While we have disclosed this construction 65 for altering the position of the spark arrester, we do not wish to be limited thereto.

The foregoing description and the drawings have reference to what may be considered the preferred, or approved form of our invention. It is to be understood that we may make such changes in construction and 70 arrangement and combination of parts, materials, dimensions, et cetera, as may prove expedient and fall within the scope of the appended claims.

Having described our invention we claim: 75

1. In a spark arrester for locomotives, the combination with a hood substantially semi-circular in side elevation and its bottom having an inlet at the front end and an outlet at the rear end; of two pairs of 80 pivotal supports connecting said hood with the boiler and permitting its movement forward to throw its inlet over the stack or rearward out of such position, manually operable means for moving the hood, a receptacle under its outlet opening, and a funnel connecting the rear end of the hood with the receptacle, for the purpose set forth. 85

2. In a spark arrester for locomotives, the combination with a hood substantially semi-circular in side elevation and having its bottom closed except for a large inlet opening at the forward end and a small outlet opening at the rearward end; of pivotal supports for sustaining this hood with its inlet 90 end over the stack and its outlet end in rear thereof and directed downward, a receptacle on the boiler beneath said outlet end, a plurality of rods pivoted at their lower ends on the boiler and pivotally connected at their 100 upper ends with the hood, each rod being in two members connected by springs tending to draw the hood normally downward, another pair of rods pivoted at their lower ends on the boiler, guides on the sides of the 105 hood through which these rods pass, and actuating mechanism at a distant point connected with these rods, for the purpose set forth.

3. In a spark arrester for locomotives, the 110 combination with a hood having its top curved to the rear and its bottom provided with an opening at the front and an outlet opening at the rear end, a smoke outlet in the top of the hood protected by a baffle 115 plate, and a plurality of supports pivoted at their lower ends on the locomotive boiler and at their upper ends to the hood; of means for swinging the hood on its supports, a funnel loosely embracing the outlet end of the hood, and a receptacle within which the lower end of the funnel is pivoted, as described. 120

4. In a spark arrester for locomotives, the combination with its hood having a top 125 curved to the rear and its bottom provided with an opening at the front and an outlet opening at the rear end, and a plurality of supports pivoted at their lower ends on the locomotive boiler and at their upper ends to 130

the hood; of means for swinging the hood on its supports, a receptacle adapted to be mounted on the boiler in rear of its stack, the top of the receptacle having a channel 5 opening out its rear end, and a spout whose lower end is pivoted in the receptacle and whose body is adapted to rise therefrom and loosely engage the outlet end of said hood, as described.

10 5. In a spark arrester for locomotives, the combination with its hood having a top curved to the rear and its bottom provided with an inlet opening at the front and an outlet opening at the rear end, and a plu-
15 rality of supports pivoted to the hood; of means for swinging the hood on its supports, a receptacle adapted to be mounted on the boiler, a spout pivoted at its lower end within the receptacle and with its larger
20 upper end embracing the outlet end of the hood having a lip projecting forward and bent upward beneath said hood, and a rib under the hood engaging said lip, as de-
scribed.

25 6. In a spark arrester for locomotives, the

combination with a hood arched to the rear from the stack and having an inlet opening fitting over the mouth of the stack and a reduced outlet at its rear end, a rocking spout whose upper end coacts with said outlet end for receiving the sparks, and a receptacle in which the lower end of the spout is pivoted; of two pairs of rods pivoted at their lower ends on the boiler and at their upper ends to the sides of said hood, a pair 35 of rods pivoted on the boiler and with their upper ends extending alongside the hood, guides on the hood within which said upper ends are loosely mounted, cross bars connecting these rods, a rod connected with one 40 of the rods and leading rearward to the cab, and actuating mechanism in the cab attached to this rod.

In testimony whereof we affix our signatures in presence of two witnesses.
